UNITED STATES PATENT OFFICE.

DAVID GESSNER, OF WORCESTER, MASSACHUSETTS.

CLOTH-PRESSING MACHINE.

1,090,611.

Specification of Letters Patent. Patented Mar. 17, 1914.

Application filed April 21, 1910. Serial No. 556,780.

To all whom it may concern:

Be it known that I, DAVID GESSNER, a citizen of the United States, and a resident of Worcester, county of Worcester, and 5 State of Massachusetts, have invented a new and useful Improvement in Cloth-Pressing Machines, of which the following is a specification.

The primary object of this invention is 10 the simplification and lightening of the machine shown in my Patent No. 565,072 dated August 4, 1896.

Figure 1 is an elevation of the gear or right hand end of the machine with the bed 15 in pressing position. Fig. 2 is an elevation of the steam or left hand end of the machine with the bed in pressing position; the lowered position of the bed plate being shown in dotted lines. Fig. 3 is an elevation 20 of the front of the machine with the folder omitted. Fig. 4 is an elevation of the rear of the machine with the folder in position. Fig. 5 is a plan view. Figs. 6, 7 and 8 are details.

25 The shaft 23 from which the bed plate pressure is produced, is operated from the hand wheel 23^a, through the pinion 23^b and gear 23^c, pinion 23^d and segmental gear 23^e. The shaft 58 from which the cylinder is 30 driven is driven by power applied through the fast and loose pulleys 58^a and 58^b. In lieu of any base plate, I use the girds 1^a, 1^b, 1^c, 1^d. There are two members of the frame each of which consists of two boxed up- 35 rights 2 and 3 and a connecting member 4 at the top. At the gear end of the machine, a web 5 connects the uprights 2 and 3 but at the steam end the uprights 2 and 3 are unconnected so as to leave a clear open space 40 A between them for the removal of the bed plate and its truss. The cylinder 7 is mounted in stationary bearings upon the members 4. The bed-plate 8 is located immediately below the cylinder and is provided 45 with end projections 9 and 10 which project into the members 2 and 3 and slide vertically in guideways on the members 4, whereby said bed plate is movable radially of the cylinder 7. Each of the bed plate projec- 50 tions 9 and 10 rests upon the crown of a stud 11 screwthreaded to the worm gear 12, which rests upon the top of a hollow column 13, which is pivoted to a lever 14 having its fulcrum on the frame at 15 and opera-

tively connected by a link 16 with an arm 55 17 fixed to the shaft 23.

The bed plate is so arranged that the central line of its pressing surface is in substantially the same vertical plane with the cylinder axis. 60

The movement for producing and releasing the bed plate pressure is produced through the connections last referred to by the oscillation of the shaft 23. As the shaft 23 is moved from the nonpressing position 65 shown in Fig. 8, to the pressing position shown in Fig. 6, the arm 17 and link 16 perform the power-multiplying and locking function of a toggle and the power is further multiplied by the lever 14. 70

In releasing the pressure, the first movement of the arms 17 serves to move the toggle 16, 17 out of its locked position of Fig. 6. Thereupon, it is necessary to apply a brake to stop the release at the desired point 75 and prevent it going too fast. This brake is shown at 40 and is held normally set by a spring 41. It is unset by a foot lever 42. The operator by the use of this brake can regulate the speed of release and stop it at 80 any point desired.

I understand this to be the first machine in which retraction of the bed plate, after being unlocked, from pressing into nonpressing position is actuated automatically by 85 the weight of the bed plate so that after the operator performs the unlocking, the weight of the bed plate does the rest until the retractive movement is stopped by the operator. In the machine shown the operator 90 unlocks the toggle by a slight movement of the hand-wheel 23^a. Thereupon, the bed plate descends under its own weight and it remains only for the operator to control the speed and extent of its descent by the foot- 95 lever 42 through the brake 40.

Fixed so as to move with the pinion 23^b is a projection or nose 43 with which a dog 44 is adapted to engage when in the position shown in Fig. 6, so as to stop the movement of the hand wheel 23^a. This dog 44 is held normally out of engagement with the projection 43 by a spring 45 but is thrust into engaging position by a projection 46 cast on the segment gear 23^e contacting with 100 an adjusting screw 47 on the arm 48 fixed to the dog. By the adjustment of the screw 47, this mechanism may be set so as to stop 105

itself as soon as the operator has moved the toggle 16, 17, into the position shown in Fig. 6 where it is in the pressing position desired.

5 The movement for adjusting the bed plate pressure is produced by turning the hand wheel 18 and thereby, through the worm gears 19 and 12 controlling the adjustment of the stud 11. The movement for lowering the bed plate to the position for its removal from the machine is produced by continuing the movement of the hand wheel 18. When this movement has continued until the bed plate slides 30, 31, rest on the 10 ledges 22, 24, the studs 11 will be relieved of the weight of the bed plate and the bed plate may be slid endwise out through the opening A and supported during such sliding by the ledges 22 and 24. While so supported and being slid, the truss of the bed plate will extend down into the space between the ledges 22 and 24. These ledges are carried by brackets fixed to the frame members 2, 3, on opposite sides of the opening A and extending, as shown in Fig. 3, 15 part way toward the opposite end of the frame.

As the bed plate descends, the downward projections 20 and 21 from the bedplate 30 descend between the ledges 22 and 24 so as to guide the bedplate in its downward movement. Then the downward projections 32 and 33 from the bedplate descend outside the ledges 22 and 24 so that as the bedplate 35 is slid out endwise on the ledges 22 and 24 they are held between the downward projections 30, 31, and 32, 33, respectively, and the bedplate is thereby held to a straight path.

40 60 is an endless apron extending between the cloth being pressed and the bed-plate and thence over the driven draft roll 61, the regulator roll 62, the tension or take-up roll 63, the idler rolls 64 and 65 and the roll 66. 45 The tension or take-up roll 63 is mounted on a slide 67 adjustable by the screw 68 at each end. The regulator roll 62 is mounted upon a swiveling support 69 enabling the axis of the roll to be swung in a plane substantially at right angles with the apron so as to cause it to bear more heavily against one side or the other of the apron as may be desired.

50 The fact that the bracket ledges 22 and 24 extend on opposite sides of the bed plate truss only part way from one end frame to the other, provides a rest for the bed plate while change of aprons is being made, which neither interferes with the transfer of the 55 apron nor with the bed plate truss.

Having thus described my invention, what I claim is:

1. In a cloth-pressing machine, in combination, a cylinder, a bed plate arranged to 65 gravitate away from the cylinder, pressure

mechanism to move the bed plate toward the cylinder, said mechanism including means to lock the bed plate in pressing position, and brake means to control the fall of the bed plate when released by the pressure mechanism. 70

2. In a cloth-pressing machine, in combination, a cylinder, a bed plate arranged to gravitate away from the cylinder, operating means for applying bed plate pressure, said means being driven by the bed plate when gravitating, and a brake means operable on said operating means to control gravitation of the bed. 75

3. In a cloth-pressing machine, in combination, a cylinder, a bed plate arranged to gravitate away from the cylinder, a pressure actuating mechanism for applying or releasing the bed plate pressure, a rotary member driven by the bed plate when gravitating, and a brake operable on said rotary member to control gravitation of said bed plate. 80

4. In a cloth-pressing machine, in combination, a cylinder, a bed plate arranged to gravitate away from the cylinder, means movable in one direction for applying bed plate pressure, said means being connected to the bed plate whereby gravitation of the latter moves said means in the opposite direction, and a brake operable on said means during gravitation of the bed plate. 90

5. In a cloth-pressing machine, in combination, a cylinder, a bed plate arranged to gravitate away from the cylinder, a pressure mechanism to move the bed plate toward the cylinder, said means including a rotary member, a brake wheel driven by the rotary member when the bed plate gravitates, and a brake operable on said brake wheel during gravitation of the bed plate. 100

6. In a cloth-pressing machine, in combination, a cylinder, a bed-plate, end frames for the cylinder, guideways for the bed-plate carried by said end frames, whereby the bed-plate is movable toward and away from the cylinder, a pair of levers, extensible studs connecting said levers and bed-plate and constituting supports for the bed-plate, said studs comprising parts having a threaded connection whereby the parts are extended and collapsed, means for operating the levers to apply or release the bed-plate pressure, a support for the bed-plate independent of the studs, and means for operating the said threaded connections to collapse the stud parts to cause the bed-plate to gravitate onto said support. 110

7. In a cloth-pressing machine, in combination, a cylinder, a bed plate, end frames for the cylinder, guideways for the bed plate carried by said end frames whereby the bed plate is movable toward and away from the cylinder, a swinging member beneath the bed plate, a two-part stud between said member and bed plate and constituting 120

a support for the bed plate, a frame support for the bed plate, means for operating said member to apply or release bed plate pressure, and means for moving simultaneously 5 the parts of said stud relative to each other whereby the bed plate may gravitate onto said frame support.

8. In a cloth-pressing machine, in combination, a cylinder, a bed plate, means for 10 moving the bed plate toward the cylinder, said means comprising a lever mechanism, a hand shaft for operating said mechanism, and an overthrow connection between said shaft and mechanism to lock the bed plate 15 in position.

9. In a cloth pressing machine, in combination, two end frames, a cylinder having stationary bearings on the upper portion thereof, a bed plate, the central line of the 20 pressing surface of which is in substantially the same vertical plane with the cylinder axis, guideways on said frames for said bed plate, a stud upon which said bed plate is supported substantially in said 25 vertical plane, a forwardly extending lever upon which the base of said stud is supported, a link extending upwardly from the forward end of said lever and hand operated power mechanism connected with the upper 30 end of said link.

10. In a cloth-pressing machine, in combination, a cylinder, a bed plate arranged to gravitate away from the cylinder, a pressure actuating mechanism for applying or 35 releasing the bed plate pressure, and a brake operable on said mechanism when the bed plate is released to control the gravitation of the bed plate.

11. In a cloth-pressing machine, in combination, a cylinder, a bed-plate, means for moving the bed-plate toward the cylinder, a hand shaft for operating said mechanism, an overthrow connection between said shaft and mechanism to lock the bed-plate in position, 45 and a stop means for the shaft to limit movement of the overthrow connection.

12. In a cloth pressing machine, in combination, a cylinder, a bed plate, a threaded stud under each end of said bed plate, a nut 50 threaded to each stud, mechanism whereby said nuts are operated simultaneously to lower said bed plate and mechanism inde-

pendent of said first-named mechanism operating through said studs whereby the pressure is applied.

55

13. In a cloth-pressing machine, in combination, a cylinder, a bed plate, a threaded stud under each end of said bed plate, a nut threaded to each stud, mechanism whereby said nuts are operated simultaneously to 60 lower said bed plate, and mechanism independent of said first-named mechanism operating through said studs whereby the pressure is applied.

14. In a cloth-pressing machine, in combination, a cylinder, a bed plate movable toward the cylinder, and means for moving the bed plate comprising a lifting lever, a rotary operating shaft, a link member connected to the said lever, and an overthrow 70 connection between said link member and operating shaft whereby movement of said shaft raises the bed plate and locks the same in position.

15. In a cloth-pressing machine, in combination, a cylinder, a bed plate movable toward the cylinder, and means for moving the bed plate comprising a lifting lever, a stud connecting the bed plate and said lever, a rotary operating shaft, a link member connected to the said lever, and an overthrow 80 connection between said link member and operating shaft whereby movement of said shaft raises the bed plate and locks the same in position.

85

16. In a cloth-pressing machine, in combination, a cylinder, a bed plate arranged to gravitate away from the cylinder, pressure means for moving the bed plate toward the cylinder and supporting the bed plate when 90 the pressure is released, an extensible and retractible connection between said means and bed plate, a bed plate support at a point below the normal support of the bed plate, and additional means for extending and re- 95 tracting said connection.

In testimony whereof, I have hereunto signed my name in the presence of two subscribing witnesses.

DAVID GEISSNER.
